M. F. BROGAN

HEEL BEVELING MACHINE

Filed Aug. 6, 1924

INVENTOR-

Michael Frank Brogan
By his Attorney,
Nelson W. Howard

UNITED STATES PATENT OFFICE.

MICHAEL FRANK BROGAN, OF LAWRENCE, MASSACHUSETTS, ASSIGNOR TO UNITED SHOE MACHINERY CORPORATION, OF PATERSON, NEW JERSEY, A CORPORATION OF NEW JERSEY.

HEEL-BEVELING MACHINE.

Application filed August 6, 1924. Serial No. 730,455.

This invention relates to cutting machines and is herein illustrated as embodied in a machine adapted to bevel the margin of a spring heel.

5 In the manufacture of shoes having soles of crepe rubber, it is customary to provide spring heels of that material. These spring heels are made by dieing out properly shaped blanks from crepe rubber sheets and 10 then beveling the forward margins of the blanks. Because of the nature of crepe rubber, this beveling operation has presented considerable difficulty and, so far as I am aware, has hitherto been performed by 15 means of a hand knife manipulated in such a manner as to produce a draw cut.

The general object of the present invention is to provide a machine by the use of which this and similar operations may be 20 performed with rapidity and precision.

Accordingly, the present invention is illustrated as embodied in a machine comprising a work-support and a rotary disk cutter which are relatively movable to cause the 25 cut to progress through the work. The illustrated work-support is movable for this purpose, and is therefore hereinafter termed a work-carrier. In the illustrated machine, the work-carrier is provided with a bed to 30 engage the attaching face of a heel blank, an abutment to engage the breast face and thereby register the heel relatively to the cutter, and with an abutment to engage one side of the periphery of the heel blank and 35 thereby push the latter widthwise past the cutter. Thus, while the work-carrier is movable lengthwise of the major dimension of a cut the cutting load at any instant is limited to the minor dimension, and when cutting 40 rubber this is preferable to minimize the distortion of the rubber, much of which is due to friction. The work-carrier is also preferably provided with a groove into which the cutter may project to cut entirely through 45 the work without touching the carrier. A heel blank supported by a carrier having a bed to engage the attaching face, an abutment to engage the breast face, and an abutment to engage one side of the periphery as 50 aforesaid, may be easily held by moderate pressure of the operator's fingers to prevent

displacement by the cutter, and since no other clamping means is needed, successive blanks may be beveled with great rapidity and accuracy.

These and other features of the invention, including certain details of construction and combinations of parts, will be described as embodied in an illustrative machine and pointed out in the appended claims.

Referring now to the accompanying drawings,

Figure 1 is a perspective of a machine in which the present invention is embodied;

Figure 2 is a perspective of a piece of work after it has been operated upon;

Figure 3 is a detail in perspective of the carrier for the blank and the guide upon which it is slidable, and

Figure 4 is a view partly in section and partly in elevation of a portion of the machine showing a heel blank in process of being operated upon.

The pedestal 5 of the machine has a segmental top 7 upon which rest two lugs, one of which is shown at 9, formed at the lower end of a generally U-shaped head 11. Cap screws, one of which is shown at 13, extending through slots in the segmental top 7 and threaded into the lugs hold the head 11 in place and permit the head to be tilted into and held in different positions. Rotatably mounted in the arms of the U-shaped head are two alined shafts one of which 15 carries at its outer end a disk cutter 17. The other shaft 18 is slidable in this bearing and carries a pulley 19. The rear end of the cutter shaft and the front face of the pulley carry complementary clutch members which may be caused to be engaged or disengaged by pushing or pulling the handle 21 on the slidably mounted square rod 23, the forward end of which has a finger extending into a groove 25 formed in the hub of the pulley 19. The particular clutch has not been shown since the details of its construction form no part of the present invention and any suitable clutch may be used. A belt, indicated by the dot and dash line, runs around the pulley 19, over idle pulleys 27 and up around a power pulley, not shown, this arrangement of belt and pulleys permitting

the head 11 to be tilted without disturbing the driving connection.

The invention includes a manually movable work-carrier upon which the article of work may be held by the operator's fingers so that one hand will be sufficient to move the carrier past the cutter and to maintain the work in the desired position thereon. Furthermore, the illustrated carrier is provided with non-confronting surfaces arranged to engage and brace the work at opposite sides of the cutter without clamping the work. Consequently, a true and accurate cut is insured and the passage of the cutter through the material, particularly through rubber, is made easier and the waste material is left free to recede from the cutter as the cut progresses.

The mounting for the work-carrier comprises an arm or fixture 29 projecting from the head 11 under the cutter, and adjustable bracket 33, 35, and a horizontal guide 39 affixed to said bracket by screws 37. A segmental slot 30 is formed in the bracket and the latter is clamped to the arm 29 by bolts 31 extending through said slot.

The work-carrier comprises a flat bed 41, preferably inclined, an abutment 43 at the lower edge of the bed to register the heel blank relatively to the cutter, and abutments 63 at the ends of the bed. The bed and the abutment 43 form a square trough to receive the initially square breast portion of a heel 100 as shown in Fig. 4, and a groove 49 is formed in the deepest part of this trough to receive a portion of the cutting edge of the cutter 17 so that the latter may cut entirely through the heel blank without touching the carrier. To obtain the groove 49 I preferably make the abutment 43 as a separate piece, form a rabbet therein, insert a spacer 45, and fasten the three parts together by screws 47. An undercut groove is formed in the back of the bed 41 to receive the guide 39, and the work-carrier is thus arranged to slide lengthwise of the aforesaid trough. The curvature of the slot 30 provides for angular adjustment of the work-carrier to vary the angle of the bevel imparted to the breast of the heel, and the groove 49 provides for cutting entirely through the heel without dulling the cutting edge.

Movement of the work-carrier in one direction is arrested by an abutment 51 affixed to one end of the guide 39, and movement in the opposite direction is arrested by the head of a screw 50 set into the guide. The work-carrier may be automatically returned to the abutment 51 by a tension spring 52 if one end thereof is attached to said abutment and the other end to a pin 53 fastened to the carrier (see Fig. 1).

To bevel the breast of a heel blank the attaching face of the blank is placed on the bed 41, the square or abrupt breast face is

placed against the abutment 43, and preferably the periphery at one side of the blank is placed against the abutment 63 that will act as a backer to brace or push the blank against the cutter.

While grasping the upper part of the work-carrier and the heel blank between the thumb and fingers of one hand and thereby pressing the blank against the bed 41, the operator may, with the same hand, slide the carrier past the cutter to bevel the breast of the heel as shown in Fig. 2.

To facilitate the cutting of rubber the machine may be equipped with means for lubricating the cutter 17. As shown, a receptacle 59 is provided for a lubricant such as oil or soapy water, and the lubricant is delivered to the cutter by a nozzle 57 having a cock 61. Also, a segmental shield 55 may be arranged to surround the upper part of the cutter so that the operator's hand will be protected.

Although the invention has been set forth as embodied in a particular machine, it should be understood that the invention is not limited in the scope of its application to the particular machine which has been shown and described.

Having thus described my invention, what I claim as new and desire to secure by Letters Patent of the United States is:—

1. A cutting machine comprising a work support having surfaces arranged to engage two angularly related meeting surfaces of an article of work, said work-engaging surfaces forming a trough, and a rotary disk cutter arranged to operate in said trough, said support and said cutter being constrained to relative rectilinear movement lengthwise of said trough to cause the cut to progress through the work.

2. A cutting machine comprising a work-support having a groove and non-confronting work-engaging surfaces at opposite sides of said groove, and a rotary disk cutter arranged to project into said groove, said support and said cutter being constrained to relative rectilinear movement lengthwise of said groove to cause the cut to progress through the work.

3. A cutting machine comprising a movable work-support having rigidly related non-confronting work-engaging surfaces forming a trough to receive the work and having a groove extending lengthwise of said trough at the deepest part thereof, a rotary disk cutter arranged to project into said trough and into said groove, and means to guide said work-support in straight lines lengthwise of said trough.

4. A cutting machine comprising a work-support having a groove and non-confronting work-engaging surfaces at opposite sides of said groove, and a cutter arranged to project into said groove, said support and said

cutter being relatively movable lengthwise of said groove and relatively adjustable to vary the angle of the plane of the cut.

5. A cutting machine comprising a work-support having a bed to engage the attaching face of a heel blank and having an abutment to engage the breast face thereof, and a cutter arranged to sever the blank with an oblique cut to produce an inclined breast face, said support and said cutter being relatively movable widthwise of a blank placed on said support as aforesaid.

6. A cutting machine comprising a work-support having a bed to engage the attaching face of a heel blank, an abutment rigidly related to said bed to engage the periphery at one side of the blank, means to engage the breast face of said blank, and a cutter arranged to sever the blank with an oblique cut to produce an inclined breast face, said support and said cutter being relatively

movable widthwise of the blank to cause the cut to progress toward said abutment from the opposite side of the blank.

7. A cutting machine comprising a work-carrier having a bed to engage one face of an article of work, and a rotary disk cutter arranged to traverse the opposite face of the article and cut the latter in two, said carrier being movable along lines parallel to the plane of said bed to effect cutting progress, said cutter being at an acute angle to said plane to produce a bevel cut, and said carrier having two work-engaging abutments one to register the article of work relatively to said cutter and the other to push the article along the lines of movement of the carrier.

In testimony whereof I have signed my name to this specification.

MICHAEL FRANK BROGAN.
